A. HENNING,
NOZZLE FOR BOTTLES, TUBES, AND THE LIKE,
APPLICATION FILED AUG. 22, 1916.

1,287,308.

Patented Dec. 10, 1918.

INVENTOR
ALBERT HENNING
BY: *Frank Oldham*
ATTORNEY.

UNITED STATES PATENT OFFICE.

ALBERT HENNING, OF LEYTONSTONE, ENGLAND.

NOZZLE FOR BOTTLES, TUBES, AND THE LIKE.

1,287,308.

Specification of Letters Patent. Patented Dec. 10, 1918.

Application filed August 22, 1916. Serial No. 116,335.

To all whom it may concern:

Be it known that I, ALBERT HENNING, a citizen of the United Kingdom of Great Britain and Ireland, and resident of 120 5 Harrow road, Leytonstone, Essex, England, have invented certain new and useful Improvements in Nozzles for Bottles, Tubes, and the like, of which the following is a specification, such as will enable others 10 skilled in art to which it appertains to make and use the same.

This invention relates to closing devices or stoppers, for capsules, ampoules, bottles, flasks, glass tubes and the like and while applicable to these articles for use with various fluids such as scents and the like is especially designed for use with flasks or tubes containing volatile liquids such as ethyl chlorid, chloroform, ether and other medicinal fluids. 15

20 The chief object of the invention is to provide means whereby the closing device can be readily attached and detached without using cement or other binding or holding agent.

25 The invention may be broadly described as consisting in so fashioning or making the end of the bottle, flask, tube or other fluid container and also the closing device that the latter may be fitted to the former by simply 30 pushing it into position and in providing means by which when the closing device is in place it will be held from accidental removal or displacement in either or both lengthwise and sideward manner.

35 In carrying the invention into effect the closing device is so made that it will, in spring-like manner inclose projections on the bottle or flask, the grip of the said device being sufficient to hold it in position against 40 any accidental displacement but not sufficient to prevent its intentional removal.

I will now describe the invention with reference to the accompanying drawings in which examples only are shown.

45 Figure 1 represents a flask or tube *a* of well known form except so far as my invention is concerned. This tube is fitted with a stopper or closing device of a type I have long used but which is specially adapted or 50 constructed to fit the outlet or capillary end of the tube.

Fig. 2 is an enlarged view of the upper part of Fig. 1 and shows more detail.

Fig. 3 is a side view of Fig. 2.

55 Figs. 4 and 5 show two views of the upper or capillary end of the tube shown in Figs. 2 and 3.

Figs. 6 and 7 show a modified form of tube and

Figs. 8 and 9 illustrate a modification.

Referring to Figs. 1 to 5 the flask or tube *a* is provided with a spherical protuberance *b* hereinafter called the ball and two side protuberances *c c* hereinafter called the ribs. The closing device has a spring controlled 60 lever-stopper *d* mounted upon a sleeve or cap *e*. The stopper *d* is adapted under pressure of spring *f*, to close the capillary or fine tube *g* but may be lifted therefrom by pressure on the lever *h*. The sleeve has in this example 65 two opposite openings *i i* and two opposite openings or slits *j j*. These slits allow for some relative spring movement of the sides or parts in which openings *i i* are made. This spring movement is sufficient to allow 70 the sleeve to be pushed down over the tube *g* so that the openings *i i* will receive opposite sides of the ball *b* and grip upon same sufficiently to hold the sleeve against lengthwise accidental movement. When the sleeve is 75 pushed into place the ribs *c c* enter the slits *j j* and prevent lateral or rotary movement of the sleeve around the tube *g*. It is thus only necessary to push the sleeve into its correct position to hold it in place at the same 80 time not preventing it being pulled off when it is desired to remove the closing device, for refilling, exchange or other such purpose. Instead of having ribs *c c*, depressions such 85 as *k k*, Figs. 6 and 7 can be provided in the 90 sides of the ball and the sleeve may have corresponding inner ribs to fit into the depressions. The ribs or some other part of the sleeve would be slit to permit of the spring-like movement above referred to.

95 If it is preferred the ball and the ribs can be made in the form of a metal cap such as *l* shown in Figs. 8 and 9. In this case the cap is permanently secured to a bottle, flask or tube with cement or other suitable adhesive. 100 A ring or washer such as *m* Fig. 2 may be employed to center the tube *g* correctly in the sleeve *e*.

105 It must be understood that the shapes of the protuberances, ribs, recesses or slits may vary as required and that the drawings illustrate examples only.

What I claim and desire to secure by Letters Patent is:—

110 1. A receptacle for liquids, having a neck provided with a discharge opening and with an exterior spheroidal portion, a sleeve grip- 115 pingly fitting over said neck and having openings which engage the aforesaid spheroid-

dal portion to prevent accidental displacement longitudinally, and coöperating means, additional to those mentioned, on said neck and said sleeve, for preventing accidental displacement rotarily, a lever and a stopper thereon to close the discharge opening.

2. A receptacle for liquids having a neck provided with a discharge opening, the root of the neck being spheroidal, longitudinal ribs on said spheroidal portion, a sleeve fitting over said neck having openings which engage the spheroidal portion and slots which engage said ribs whereby said sleeve is prevented from accidental displacement either longitudinally or rotarily, a lever and a stopper thereon to close the said opening.

3. A receptacle for liquids having a neck

provided with a discharge opening, the root of the neck being spheroidal, longitudinal ribs on said spheroidal portion, a sleeve fitting over said neck having openings which engage the spheroidal portion and slots which engage said ribs whereby said sleeve is prevented from accidental displacement either longitudinally or rotarily, a lever pivotally mounted upon the sleeve, a stopper thereon and spring means adapted to close the stopper over said opening.

In witness whereof I have hereunto set my hand in presence of two witnesses.

ALBERT HENNING.

Witnesses:

LILY PARRY,
HENRY FAIRBROTHER.
